[57] CLAIM

The ornamental design for a buffet dinner plate, as shown and described.

DESCRIPTION

FIG. 1 is a top, front, and left side perspective view of a buffet dinner plate showing my new design;

FIG. 2 is a top plan view thereof;

FIG. 3 is a front elevational view thereof, the rear elevational view being a mirror image;

FIG. 4 is a left side elevational view thereof;

FIG. 5 is a right side elevational view thereof.

FIG. 6 is a bottom plan view thereof.

FIG. 7 is a top, front, and left side perspective view of a second embodiment of my new design for a buffet dinner plate;

FIG. 8 is a top plan view of FIG. 7;

FIG. 9 is a front elevational view of FIG. 7, the rear elevational view being a mirror image;

FIG. 10 is a left side elevational view of FIG. 7;

FIG. 11 is a right side elevational view of FIG. 7; and

FIG. 12 is a bottom plan view of FIG. 7.
